Fig. 9

FIG. 1 is a plan view of one embodiment of the artificial fishing lure design of the present invention;

FIG. 2 is a view similar to FIG. 1, showing the lure as it moves forwardly (to the right);

FIG. 3 is a view similar to FIG. 1, showing the lure as it moves rearwardly (to the left);

FIG. 4 is a slightly inclined elevation of the lure of FIG. 1;

FIG. 5 is a rear elevation of the lure of FIG. 1;

FIG. 6 is a bottom view of the lure as it is shown in FIG. 3;

FIG. 7 is a plan view of a modified embodiment of the fishing lure of the present invention;

FIG. 8 is a slightly inclined elevation of the lure of FIG. 7; and

FIG. 9 is a front elevation of the lure of FIG. 7.

This application is a division and a continuation-in-part of copending U.S. Patent Application, Ser. No. 239,-

843, filed Mar. 30, 1972, for Artificial Fishing Lure, now Pat. No. 231,528.

I claim:

The ornamental design for an artificial fishing lure, as shown and described.
